UNITED STATES PATENT OFFICE.

CHARLES H. MORAND, OF LOS ANGELES, CALIFORNIA.

FOLDING DROP-STEP FIRE-ESCAPE.

1,069,975.

Specification of Letters Patent. Patented Aug. 12, 1913.

Application filed April 15, 1912. Serial No. 691,041.

To all whom it may concern:

Be it known that I, CHARLES HARRISON MORAND, a citizen of the United States, residing at Los Angeles, in the county of Los Angeles and State of California, have invented a new and useful Folding Drop-Step Fire-Escape, of which the following is a specification.

An object of this invention is to provide a fire escape applicable for the first story of buildings and to so construct the fire escape that it may be folded up against the building so as not to be available for burglars to enter the second story, said fire escape being readily lowered when required for descent of persons from the second story to the ground.

Objects of the invention are to produce a metallic fire escape of this kind of minimum weight which will be perfectly safe for the use of women and children, which will be attachable to the lower platform of the usual fire escapes and can be brought from the folded position into position for use and vice versa, with great ease, convenience and celerity.

Other objects of this invention may appear from the subjoined detail description.

The invention may be embodied in different forms.

The accompanying drawings illustrate the invention in a form I at present deem preferable.

Figure 1 is a broken front elevation of a folding fire escape attachment embodying the invention mounted for operation upon the standard fire escape of a building. Fig. 2 is a fragmental broken sectional elevation viewed from line x^a , Fig. 1. The lower broken parts are offset relative to the intermediate parts of the view to economize space. Dotted lines in Figs. 1 and 2 indicate the folded and locked position of the attachment when not in use. Fig. 3 is an enlarged fragmental plan of two steps viewed from line x^a , Figs. 1 and 2. Fig. 4 is a fragmental plan on reduced scale showing, in the dotted position from line x^a , of Figs. 1 and 2, the bottom step in the position it assumes upon the top hand rail of the fire escape landing when the attachment is folded up. Fig. 5 is an enlarged fragmental plan view from line x^b , Figs. 1 and 2, illustrating the adjustable spacing means for the side rails. A part of each side bar is shown in axial section for clearness of illustration. Fig. 6 is a fragmental sectional de-

tail of the joint between the hand rail standards and the side bars.

The side rails 1 may be constructed of metal pipe or other suitable material and are provided at their upper ends with hinge knuckles 2 to receive pins 3 for attachment to the support knuckles 4 adjustable along and carried by a rail support which may be the lower platform 5 of an ordinary fire escape landing fastened to the wall 6. Said side rails are of sufficient length to reach the ground while standing aslant and are hinged at their upper ends to the support.

The steps 7 are metal plates arranged to run along the side rails 1 preferably being provided with elongated eyes 8 through which said rails are passed. Flexible or collapsible step connections 9 and 9' support the steps, the upper step being connected by connection 9' with the support through the side rails; and the connections 9 being fastened to and extending between the front edge of each step and the rear edge of the step next below in succession from top to bottom of the ladder, so that as the side rails are lowered into position aslant as shown in Fig. 2 the steps will run down along the side rails and come to rest properly spaced apart to form a stairway or step-ladder. Top and bottom hand rail standards 10 and 11 are hinged by knuckles 12, 13 and pins 14 to the side rails; and the hand rails 15 are in like manner hinged at 16 to the tops of the hand rail standards. Flexible stays 17 are connected to the main support to limit the downward movement of the hand rails relative to the side rails, so that when the side rails are lowered to rest on the ground the standards of the hand rails will be about normal to the side rails. The support and lower step 7' are provided with inter-engaging step-retaining means as the pins 18 and the catches 19, said catches preferably being holes 20 through the top rail or hand rails 21 of the second story landing at 5, to receive the pins.

A line 22 is connected at its lower end with the side rails and led thence upward to a windlass device 23 fastened to the support. The windlass drum 23 may be provided with a spur gear 24 driven by a pinion 25 meshing therewith and having a crank 26. Said drum 23 may be journaled on an axis 27 fixed to the wall 6 and may be locked from rotation by a pin 28 slidable through the drum parallel with the drum

axis and seatable in a socket 29 in the wall. Stop pins 31 are provided in each side rail and engage the top step when the attachment is in the stored position to thereby support the remaining steps above the top standard 10 of the hand rail. The side rails are adjusted toward and from one another by means of adjusting rods 32 having right and left handed threads 33 and 34 extending through threaded holes in the side rails thereby alining the same with the eyes 8 of the steps.

When it is desired to store the drop fire escape, the windlass will be turned to wind up the line, thus drawing the side rails into vertical position at the lateral upward movement of such rails. When the side rails are nearly vertical, the attendant will lift the lower step to allow it to pass above the plane of the top rail 21 of the landing, so that the pins 18 can be inserted into the holes 20, and said step is then lowered onto the top rail, thereby normally closing the platform exit or cutaway portion 30 in the top rail and locking the attachment in its folded position. The apparatus is then out of the way.

When it is desired to use the fire escape, the bottom step will be raised to disengage it from the top rail 21 and by means of the windlass the side rails may be gradually lowered to the ground, and as this occurs the steps by gravity assume the position for use.

The fire escape may be mounted upon the platform 5 either to swing out from a building or parallel to it, the latter form being shown in the drawings.

The top rail or hand rail 21 of the landing is cut away at the side rails to make a passage way from the landing to the steps when the side rails are lowered and when the side rails are in upright position the steps close the opening at the cut-away portion of the landing or balcony railing. The stop pins 31 are preferably so located on the side rails with relation to the hinge knuckles thereof and the pile of steps that is formed when the steps run together in the folded position, that the steps form a closure for the passage-way when the apparatus is in its folded position. The bottom step which thus is brought to the top of the pile is outwardly widened from the side rails so that when it is in the inverted position it overhangs the top rail 21 of the landing so that the interengaging step-retaining means, as the pins 18 and holes 19, can be brought into engagement.

It is understood that the side rails may be hinged directly to a building as in front of a window sill, in which instance the window sill would take the place of the landing platform, but such variations of arrangement are not necessary to be illustrated.

During installation of the fire escape the pins 18 may be brought into exact registration with the holes 20 by adjusting the knuckles 4 along the lower platform 5, and the exact spacing of the side rails 1 may be effected by turning the adjusting rods 32 in the appropriate direction so that the steps 7, 7' will slide easily along the side rails without binding. These adjustments are important for the reason that in structural work where the assembling of the parts is done partly in the shop and partly in the field, the rough character of the work precludes nice adjustments of the parts in the shop.

I claim:

1. A collapsible fire escape comprising side rails adapted to be raised and lowered, steps mounted to run on the side rails, flexible step connections to space the steps along the side rails, a support to which the side rails are hinged, a hand rail mounted on the support and provided with a cutaway portion, and means to engage the lower one of said steps to close the cutaway portion when the side rails are raised.

2. A collapsible fire escape comprising side rails adapted to be raised and lowered; steps mounted to run on the side rails; flexible step connections to space the steps along the side rails; a support to which the side rails are hinged; an interrupted hand rail mounted on the support; and means to retain the steps intermediate of the ends of the side rails and between the support and the hand rail at the interruption when the side rails are raised.

3. A fire escape comprising a support, a hand rail mounted on the support and provided with a cut-away portion forming an exit, side rails hinged to the support to swing up and down, and steps mounted to run on the side rails and spaced apart to form a stairway when the side rails are swung down, said steps running toward each other and into the space between the support and the cut away plane of the hand rail.

4. In a drop step fire escape, the combination with hinged side rails therefor, of steps provided with elongated eyes to accommodate the side rails in a slanting position.

5. In a drop step fire escape, the combination with hinged side rails therefor, of steps having elongated eyes, through which the side rails pass, and flexible connections fastened to and extending between the front edge of each step and the rear edge of the step next below in succession from top to bottom of the side rails.

6. A drop side fire escape comprising a support, side rails hinged to the support in a normally upstanding position, a hand rail for said support the same being cut away at the side rails and provided with holes, steps running on the side rails, and pins in

the lower one of said steps to normally engage the hand rail holes for the purpose set forth.

7. A fire escape comprising a platform, 5 side rails hinged to the platform, steps running on the side rails, flexible connections between the steps, and means to temporarily hold the side rails upright when swung above the platform.
- 10 8. A fire escape comprising a platform, side rails hinged to the platform, steps having holes through which the side rails are passed, flexible connections between the steps, flexible means supporting the topmost 15 step, a stop above the topmost step to support the steps when the side rails are swung up above the platform, and means to hold the side rails in upright position and folded above the platform.
- 20 9. A fire escape comprising a support, rails hinged to the support, steps running on the rails, flexible connections between the steps to space them apart along the rails, means to support the topmost step, standards, pins extending at right angles to the 25 side rails and hinging the standards to the side rails, hand rails on the standards and foldable toward and from the side rails, connections to support the hand rails when the side rails are lowered, and means to hold the side rails in folded position.
- 30 10. A fire escape comprising a support, rails hinged to the support and adapted to

be lowered and raised, steps running along the rails, flexible connections between the 35 steps to space them apart along the rails when the rails are lowered, a support for the topmost step, a windlass and a connection between the windlass and the side rails for the purpose of raising and lowering the 40 side rails.

11. In a fire escape the combination with side rails and steps on said rails, of means to space the side rails apart, standards hinged to the side rails and foldable toward 45 and from the same, hand rails hinged to the standards, and means to hold the standards from folding toward the side rails when the side rails are in position for use.

12. In a fire escape; the combination with 50 a support; of a ladder hingedly connected at one end to the support; a drum on the support; a connection between the drum and the ladder; means to turn the drum to wind the connection to raise the ladder; there being a socket in the support; and a pin slideable through the drum into the socket to lock the drum.

In testimony whereof, I have hereunto set my hand at Los Angeles, California, this 60 8th day of April, 1912.

CHARLES H. MORAND.
